UNITED STATES PATENT OFFICE.

CHARLES BLAKSLEY DAVIS, OF CHICAGO, ILLINOIS.

MAIL-BAG CATCHER.

1,250,808.

Specification of Letters Patent. Patented Dec. 18, 1917.

Application filed September 10, 1917. Serial No. 190,631.

To all whom it may concern:

Be it known that I, CHARLES BLAKSLEY DAVIS, a citizen of the United States, and a resident of Chicago, in the county of Cook and State of Illinois, have invented a new and useful Improvement in Mail-Bag Catchers, of which the following is a specification.

My invention relates to improvements in mail bag catchers, and it consists in the constructions, combinations, and arrangements herein described and claimed.

An object of my invention is to provide an automatic mail bag catcher which is so arranged that after it has once been set by the mail clerk, no further attention need be paid to it, thus obviating the necessity of standing by the mail bag catcher and "sighting" it at a mail bag suitably supported at a way station.

Another object of the invention is to provide a mail bag catcher which normally lies against the side of the car when not in use, the mail bag catcher including a trip is adapted to be struck by a mail bag when the device is set, the impact of the mail bag causing the trip to collapse and automatically throw the bag into the car.

Another object of the invention is to provide a mail bag catcher which may be interchanged from one side of the car to the other, duplicate hinge castings being attached to the sills of the car doors on each side.

Other objects and advantages will appear in the following specification, reference being had to the accompanying drawings, in which:

Figure 1 is a side elevation of a portion of a car showing the improved casting applied to the doorway.

Fig. 2 is a cross section on the line 2—2 of Fig. 1 looking in the direction of the arrows.

Fig. 3 is an enlarged side elevation of the mail bag catcher as it appears when viewed from the inside, and

Fig. 4 is a longitudinal section taken on the line 4—4 of Fig. 3 and looking in the direction of the arrows.

In carrying out my invention, I provide a trap frame 1 which is located across one or the other of two doors 2 of a mail car 3. The trap frame 1 may be constructed of any suitable material that is strong enough to withstand the rough usage to which the de-

vice is to be put, and preferably is constructed of channel steel somewhat as indicated in the drawings.

The trap frame 1 comprises parallel members which converge at the front and form a throat piece 4 which is curved slightly outwardly as indicated in Fig. 4. The trap frame 1 is supported on a frame support 5 which carries supporting bars 6 to which the parallel members of the trap frame 1 are hinged at 7.

The supporting bars 6 are secured to the frame support 5 in any suitable manner, and the frame support 5 may consist either of a solid bar or a pipe. The frame support 5 carries hooks 8 which are fitted into the castings 9^a secured to the rounded portion of one of the vertical door sills 2. The castings 9^a are duplicated in each door of the car, and obviously the bag catching device may be applied to either side of the car so that bags may be caught when the train is traveling in either direction.

A trip 9 is hinged at 10 to a cross bar 11 of the trap frame 1. The trip 9 consists of parallel members which are curved toward the car 3, as indicated in Fig. 4, and are spaced apart for suitably arranged space bars 12.

Recoil springs 13 are riveted to the ends of the trip members 9, and the recoil springs are curled at their free ends and adapted to engage one of a plurality of brace bars 14 of the trap frame 1 as shown in Figs. 3 and 4. A trip bar 15 is pivoted at one end to ears 16 secured to one of the bars 12 of the trip 9. The other end of the trip bar 15 is pivoted to the fulcrum stud 17 of an arm 18 loosely mounted on the frame support 5.

Links 19 are connected between the fulcrum stud 17 and a stud 20 which passes through ears 21 secured to a bar 22 of the trap frame 1. Leaf springs 23 are secured at their ends, to the frame support 5 and to the bar 22 of the trap frame 1, the springs 23 being designed to thrust the throat end 4 of the trap frame 1 against the side of the car 3 in the normal position indicated in Fig. 4.

The trap frame 1 is additionally braced at 25 at the front, and by cross braces 24, which span one of the brace bars 25 at the front, and the bars 14 and 22, respectively.

The operation of the device is as follows. The trap frame 1 is set to the position indicated in dotted lines in Fig. 4, to catch a

mail bag M. The trip 9 is pulled out to bridge the space between the throat piece 4 and the car 3. In pulling the trip 9 out, the trip bar 15 also pulls upon the fulcrum stud 17 and moves it in advance of a line drawn between the pivotal point and the links 19 on the stud 20 and the frame support 5, in which position, the links 20 and the arms 18 are held by the engagement of a lug 26 on one of the links 19, with the arm 18.

The trap frame 1 is held in this position by the tension of the leaf springs 23, the position of the links 19 with respect to the arm 18 being also maintained by the pressure of the leaf springs 23. The car 3 in traveling toward the place where the mail bag M is hung, carries the trap frame toward the bag which enters the throat of the device and strikes the trip 9. The impact of the bag against the trip 9, causes the links 19 and arm 18 which are braced against each other, to collapse, whereupon the leaf springs 23 quickly thrust the trap frame 1 toward the side of the car 3 and throw the mail bag M through the doorway 2 into the car.

The operation of catching the mail bag M is entirely automatic. The trap frame 1 is set to the position indicated in dotted lines in Fig. 4, and no further attention need be paid to the device. The car and the catching device in advancing toward the mail bag M, receive the bag in the throat formed between the trap 1 and the side of the car, where the trip 9 which holds the trap frame 1 away from the car, is struck and causes the collapse of the link members that hold the trap frame open. The trip bar 15 pulls the trip 9 back to the position indicated in full lines in Fig. 4, after the trap frame 1 has moved inwardly toward the car. The shock of returning the trip 9 is absorbed by the recoil spring 13 which is carried by the trip and which engages the bar 14 of the trap frame.

While the construction and arrangement of the device as illustrated in the accompanying drawings are those of a generally preferred form, obviously modifications and changes may be made without departing from the spirit of the invention or the scope of the claims.

I claim:

1. In a mail bag catcher, a trap frame having a pivotal support and being disposed across the doorway of a car, a spring normally urging the trap frame toward the car, a trip pivoted to the inner face of the trap frame and extending approximately to the side of a car when the catcher is in operative position, and link devices connected with the trip and holding the trap frame open against the tension of the spring when set, the end of the trap frame and the trip forming a throat for receiving a bag,

the trap frame projecting the bag through the doorway upon striking the trip and releasing the link devices.

2. In a mail bag catcher, a frame support disposed in the doorway of a car, a trap frame pivoted on the frame support and including a curved throat piece, a spring secured to the trap frame and the frame support to normally press the throat piece against the side of the car, link devices for bracing the trap frame in the open position, a trip pivoted to the trap frame at the base of the throat piece and extending toward the door opening to form a passage for the mail bag, and a trip bar connected to the trip and the link devices, to collapse the bracing connections of the link devices and obtain the automatic projection of a mail bag through the door opening under the tension of the spring.

3. In a mail bag catcher, a frame support disposed in the doorway of a car, a trap frame pivoted on the frame support and including a curved throat piece, a spring secured to the trap frame and the frame support to normally press the throat piece against the side of the car, link devices for bracing the trap frame in the open position, a trip pivoted to the trap frame at the base of the throat piece and extending toward the door opening to form a passage for the mail bag, a trip bar connected to the trip and the link devices, to collapse the bracing connections of the link devices and obtain the automatic projection of a mail bag through the door opening under the tension of the spring, and a recoil spring carried by the trip.

4. In a mail bag catcher, a frame support, hooks on the frame support, castings for receiving the hooks, said castings being secured to a door sill of a car door opening, a supporting bar secured to the frame support, a trap frame pivoted to the supporting bar, links pivoted to the trap frame and having a fulcrum stud, an arm loosely mounted on the frame support and pivoted on the fulcrum stud, a trip pivoted on the trap frame, a trip bar pivoted to the trip and the fulcrum stud, a lug on one of the links to brace the links against the arm when the trap frame is in open position, and a leaf spring secured at one end to the frame support and at the other end to the trap frame to normally urge the trap frame toward the car.

5. In a mail bag catcher, a swinging and spring pressed frame, a trip pivoted to the frame, a loosely mounted arm having a fulcrum stud, links pivoted on the stud and to the frame, and a bar having one end pivoted to the trap and its other end to the fulcrum stud of the said arm.

6. In a mail bag catcher, a support having arms and adapted to be secured to a car,

a frame pivoted to the arms of the support, springs secured to the arms and frame, a trip pivoted to the frame, an arm mounted to swing on the support, links pivoted to the arm and frame, and a bar having one end pivoted to the trip and its other end to the said arm.

7. A mail bag catcher comprising a trap frame consisting of parallel members converging at the front to form a throat piece, the end of the throat piece being curved outwardly, brace bars for the parallel members of the trap frame, a frame support having hooks for removable connection with supporting means carried in a car door opening, the parallel members of the trap frame being pivotally supported on the frame support, a spring secured to the frame support and to the trap frame to normally urge the

throat piece into engagement with the side 20 of the car, an arm loosely mounted on the frame support, links carried by the trap frame, a fulcrum stud connecting the links and the arm, the fulcrum stud being arranged to stand in advance of a line drawn 25 between the pivotal point of the links on the trap frame and the frame support, a lug carried by one of the links for engaging the arm when the trap frame is open, a trip carried by the trap frame and forming a closure 30 for the throat formed between the throat piece and the side of the car when the trap frame is open, a trip bar pivoted to the fulcrum stud and the trip to brace the bracing connections of the links and the arm upon 35 the impact of a mail bag with the trip, and a recoil spring carried by the trip.

CHARLES BLAKSLEY DAVIS.
